JUICER

Lothar Hutzler, Long Beach, N.Y., assignor to Hutzler Manufacturing Company, Long Island City, N.Y.

Filed July 28, 1970, Ser. No. 24,181

Term of patent 7 years

Int. Cl. D7—05

U.S. Cl. D89—1

FIG. 1 is a top perspective view of a juicer showing my new design;

FIG. 2 is a top plan view;

FIG. 3 is a side elevational view;

FIG. 4 is a right end elevational view; and

FIG. 5 is a left end elevational view.

I claim:

The ornamental design for a juicer, as shown.
